DOOR HOLDER

Carl S. Aspinwall, Chicago, Ill., assignor to
Norton Lasier Company, Chicago, Ill., a corpora-
tion of Illinois

Application June 3, 1940, Serial No. 338,529

16 Claims. (Cl. 16—49)

This invention relates to improved holding means for doors and similar devices where an arm is used to connect the door to a door frame, and in particular to installations where a slide connection is used.

This invention further relates to an adjustable stop for limiting the opening movement of a door and adjustable holding means for holding the door in an open position.

It is, therefore, an object of the present invention to provide a door holding device which is particularly suited for use with slide connections for doors.

It is another object to provide a door holder which may be readily adjusted to alter the position in which the door may be held open.

It is a further object to provide a door holder which may be easily rendered operative or inoperative, and which is provided with a stop for limiting the opening movement of a door when the holder is in inoperative position.

It is another object to provide a door holder which operates with a minimum amount of vibration and noise.

It is a further object to provide a door holder which may be easily assembled on a slide bar without the aid of tools.

It is another object to provide a door holder which cooperates with a stop, both of which may be regulated by a single adjustment.

These and other objects not specifically enumerated are contemplated for this invention, as will be apparent to one skilled in the art as the following description proceeds.

In the drawings—

Figure 1 is a perspective view of a holding device constructed and installed on a door in accordance with the present invention.

Figure 2 is a side elevational view of a slide connection with the holding means in holding position.

Figure 3 is a fragmentary view in cross section of a slide connection and holding means.

Figure 4 is a fragmentary view in cross section showing the holding means in inoperative position.

Figure 5 is a cross sectional view taken on the line 5—5 of Figure 3.

Figure 6 is an end elevation of a device embodying this invention.

Referring to the drawings, a bracket or frame 9 is positioned within a cut-out portion 10 in the upper edge of a door 11. The frame may be formed from a single strip of metal having an upright portion 12 and a base portion 13. End 55

members 14 and 15 may be formed by bending upwardly the ends of the base 13. The base has openings to receive screws 16 which secure the frame to the cut-out portion of the door.

5 A slide bar 17 has journals 18 and 19 which are supported by suitable journal bearings provided by the ends 14 and 15. The slide bar may be of any cross section and is substantially square in the present embodiment. The bar may be maintained in supported engagement with the frame in any suitable manner, such as by a slip 20 engaging the end 15 of the frame and a shoulder on the bar. An inwardly extending finger 21 may be provided by the upright portion 12 for engaging the bar and limiting its rotation with respect to the frame.

The bar 17 has a threaded portion 24 adjacent one end on which is screwed a stop or spring seat 22 which is provided with an internal annular groove 23. A coil spring 25 is slidably mounted on the bar adjacent the spring seat 22.

A crosshead or slide 26 is slidably mounted on the bar 17 and is provided with bearing surfaces which conform to the cross sectional shape of the bar. The slide is provided with a spindle 27 on which an operating arm 28 is pivotally mounted, and a pin 29 holds the arm on the spindle.

The undersurface of the slide bar is provided 30 with a channel or groove 30 which is of sufficient width to accommodate a curved resilient holding member 31. The holding member 31 has a downwardly turned portion 32, the end of which engages the annular groove 23 of the seat 35. The coil spring 25, through which the member 31 extends, may support the member in such a manner that the free end 33 of the member is maintained in engagement with a cam rod 34.

The cam rod 34 extends substantially the length 40 of the groove 30. One end of the rod extends through a hollow portion of bar 17 and through end member 14, terminating in a turned-down portion or crank 35. The rod is provided with a notch in its narrow surface for engaging a bearing pin 36 which extends across the groove 30 adjacent the end. The rod 34 has a width greater than its thickness so that when it is turned up on edge by movement of the crank 35, the notched edge of the rod engages the pin and the narrow edge of the rod cams the end 33 of holder 31 downwardly. When the crank is turned the other way, as illustrated in Figure 6, the broader side of the rod engages the pin and the end 33 of the holder is permitted to move upwardly under the influence of coiled spring 25 which has previously

been distorted by the downward thrust of holder 31. It will be noted that it is not essential that the coil spring return the holder in the manner described since the slide will move it up as it passes over the holder.

In operation, as the door 11 is opened, the bar 17 moves with it and the arm 28, which is secured at one end to the door frame, causes the slide 26 to move toward the holding member 31. When cam rod 34 is in the position shown in Figure 2, with its wider surface in a vertical position, it holds the central portion of the resilient holder 31 below the margins of groove 30. As the slide reaches the holder it passes over the end 33 until the lower surface of the slide wedges against the undersurface of holder 31. The holder being resilient, the slide is frictionally engaged and held with a minimum of noise and vibration. A slight pressure on the door will release the slide and permit the door to be returned to a closed position.

To render the holder inoperative, the crank 35 is moved so that the wide surface of the cam rod 34 is in a horizontal position, thereby permitting the holder to be moved upwardly in the groove 30 as the slide passes over it. The slide 26 may now pass over the holder 31 until it engages and compresses coil spring 25 against the spring seat 22.

The position of the holder as well as the coil spring and spring seat may be altered as a unit by merely screwing the spring seat 22 in the desired direction. This may be easily accomplished after the device has been installed in a door by rotating the spring seat, which is readily accessible from the top of the door. The downwardly turned end 32 of the holder freely rides in the annular groove 23 of the spring seat as it is revolved.

It will be noted that when the holder is in inoperative position it is not necessary that all of member 31 be maintained within the groove 30, since slide 26 will force the protruding portion up in the groove as it passes over that portion of the slide bar, provided the holder does not extend down far enough to bind the slide and frictionally hold it, as when it is in operative position.

The curved shape of holder 31 and its resiliency permit the slide to become gradually engaged and disengaged as it approaches and recedes from a holding position, with the resultant smooth and quiet operation of the device.

It will be further noted that simplicity of construction of this device enables it to be completely assembled and installed without tools, after the frame has been secured to the door.

It is to be understood that the invention is not limited to the exact embodiment of the device shown, which is merely by way of illustration, and other forms of the device will be apparent to those skilled in the art without departing from the spirit of this invention or the scope of the claims.

What is claimed is:

1. A device of the character described, comprising a door member, a door frame member, a slide bar mounted on one of said members, a slide mounted on said bar, means for connecting said slide to the other of said members, means for limiting the movement of said slide with respect to said bar, and a resilient member for frictionally binding and holding said slide as it approaches the limit of its movement.

2. A device of the character described, comprising a door member, a door frame member, a

slide bar mounted on one of said members, a slide mounted on said bar, means for connecting said slide to the other of said members, a stop for limiting the movement of said slide, and resilient means carried by said stop for engaging and holding said slide as it reaches the limit of its movement.

3. A device of the character described, comprising a door member, a door frame member, a slide bar mounted on one of said members, a slide mounted on said bar, means for connecting said slide to the other of said members, a stop for limiting the movement of said slide, rotatably mounted on said bar, and means carried by said stop in non-rotatable relation to said bar for engaging and holding said slide as it reaches the limit of its movement.

4. A device of the character described, comprising a door member, a door frame member, a slide bar having a longitudinal groove mounted on one of said members, a slide mounted on said bar, means for connecting said slide to the other of said members, a holding member for frictionally engaging said slide mounted within said groove, and means for moving a portion of said holding member beyond said groove for engagement with said slide.

5. A device of the character described, comprising a door member, a door frame member, a slide bar having a longitudinal groove mounted on one of said members, a slide mounted on said bar, means for connecting said slide to the other of said members, a holding member for frictionally engaging said slide mounted within said groove, means rotatably mounted on said bar for varying and maintaining the longitudinal position of said holding member within said groove, and actuating means for moving a portion of said holding member beyond said groove for engagement with said slide.

6. A device of the character described, comprising a door member, a door frame member, a slide bar mounted on one of said members, a slide mounted on said bar, means for connecting said slide to the other of said members, a resilient holding member for frictionally engaging said slide, means provided with an annular groove rotatably mounted on said bar for varying and maintaining the longitudinal position of said holding member with respect to said bar, and means provided by said holding member for engaging said groove.

7. A device of the character described, comprising a door member, a door frame member, a slide bar mounted on one of said members, a slide mounted on said bar, means for connecting said slide to the other of said members, a spring seat rotatably mounted on said bar, a coil spring mounted on said bar adjacent said spring seat, and a resilient holding member for frictionally engaging said slide extending through said coil spring and having one end connected to said spring seat.

8. A device of the character described, comprising a door member, a door frame member, a slide bar mounted on one of said members, a slide mounted on said bar, means for connecting said slide to the other of said members, a holding member for frictionally engaging said slide, means for supporting one end of said holding member, and actuating means engaging the other end of said member for moving the intermediate portion of said member into the path of said slide.

9. A device of the character described, com-

prising a door member, a door frame member, a slide bar having a longitudinal groove mounted on one of said members, a slide mounted on said bar, means for connecting said slide to the other of said members, a holding member for frictionally engaging said slide mounted within said groove, actuating means for moving a portion of said holding member beyond said groove for engagement with said slide, and means for maintaining said holding member in engagement with said actuating means.

10. A device of the character described, comprising a door member, a door frame member, a slide bar having a longitudinal groove mounted on one of said members, a slide mounted on said bar, means for connecting said slide to the other of said members, a holding member for frictionally engaging said slide mounted within said groove, means for moving a portion of said holding member beyond said groove for engagement with said slide, and means for retracting said portion into said groove to render said holding member inoperative.

11. A device of the character described, comprising a door member, a door frame member, a slide bar mounted on one of said members, a slide mounted on said bar, means for connecting said slide to the other of said members, a resilient holding member for engaging and binding said slide, means for moving said holding member into and out of operative position, and a spring and spring seat for limiting the movement of said slide when said holding member is in inoperative position.

12. A device of the character described, comprising a door member, a door frame member, a slide bar having a longitudinal groove mounted on one of said members, a slide mounted on said bar, means for connecting said slide to the other of said members, a holding member for engaging said slide mounted within said groove, and means for moving a portion of said holding member beyond said groove comprising a cam member mounted within said groove having one surface in engagement with the inner surface of said groove and having its opposite surface in engagement with said holding member.

13. A device of the character described, comprising a door member, a door frame member, a

slide bar mounted on one of said members, a slide mounted on said bar, means for connecting said slide to the other of said members, a resilient holding member having a curved surface for engaging and binding said slide, and means for moving a portion of said curved surface into and out of the path of said slide.

14. A device of the character described, comprising a door member, a door frame member, a slide bar having a longitudinal groove mounted on one of said members, a slide mounted on said bar, means for connecting said slide to the other of said members, a holding member for engaging said slide mounted within said groove, and means for actuating said holding member comprising a cam member having surfaces of unequal width mounted within said groove, and means for selectively moving one of said surfaces into engagement with said holding member.

15. A device of the character described, comprising a door member, a door frame member, a slide bar having a longitudinal groove mounted on one of said members, a slide mounted on said bar, means for connecting said slide to the other of said members, a holding member for engaging said slide mounted within said groove, and means for actuating said holding member comprising a cam member having surfaces of unequal width mounted within said groove, means for selectively moving one of said surfaces into engagement with said holding member, and means for maintaining another of said surfaces in engagement with the inner surface of said groove.

16. A device of the character described, comprising a door member, a door frame member, a slide bar mounted on one of said members, a slide mounted on said bar, means for connecting said slide to the other of said members, a holding member having a portion extending into the path of said slide for engagement therewith and having an end portion positioned out of the path of said slide whereby said slide may be moved beyond said end portion, and means operatively connected to said holding member for maintaining the position of said member with respect to said slide bar comprising a nut threaded to said bar.

CARL S. ASPINWALL.
